ATTORNEY

UNITED STATES PATENT OFFICE.

WILLIAM WELD HARRIS, OF NEW YORK, N. Y., ASSIGNOR TO THE MAX HUNCKE CHEMICAL COMPANY, OF SAME PLACE.

DESIGN FOR A CATHETER.

SPECIFICATION forming part of Design No. 33,456, dated October 30, 1900.

Application filed October 8, 1900. Serial No. 32,450. Term of patent 14 years.

To all whom it may concern:

Be it known that I, WILLIAM WELD HARRIS, a citizen of the United States, residing at New York, in the county of New York and State of New York, have invented and produced a new and original Design for a Catheter; and I do hereby declare the following to be a full, clear, and exact description of the invention, such as will enable others skilled in the art to which it appertains to make and use the same.

Referring to the accompanying drawings, Figure 1 is an elevation of a catheter embodying my design; Fig. 2, a cross-section at the line $x-x$ of Fig. 1; Fig. 3, a cross-section at the line $y-y$ of Fig. 1, and Fig. 4 a cross-section at the line $z-z$ of Fig. 1.

Similar numerals of reference denote like parts in the several figures of the drawings. The essential features of my design are the

continuously-coiled portion 1, having its coils all uniformly distended, the continuously-coiled portion 2, adjoining the portion 1 and having its coils abutting closely against each other, and the plain cylindrical tubular portion 3, adjoining the portion 2. It will be apparent from Figs. 2, 3, and 4 that the parts 1, 2, and 3 when viewed in cross-section will present a circular appearance.

Having described my invention, what I claim as new, and desire to secure by Letters Patent, is—

The design for a catheter, as herein shown and described.

In testimony whereof I affix my signature in presence of two witnesses.

WILLIAM WELD HARRIS.
